DANIEL KELLOGG, OF YPSILANTI, MICHIGAN.

Letters Patent No. 84,832, dated December 8, 1868.

IMPROVEMENT IN CLOTHES-BOILERS.

The Schedule referred to in these Letters Patent and making part of the same.

To all whom it may concern:

Be it known that I, DANIEL KELLOGG, of Ypsilanti, in the county of Washtenaw, and State of Michigan, have invented a new and useful Improvement in Clothes-Boilers; and I do hereby declare that the following is a full, clear, and exact description thereof, which will enable others skilled in the art to make and use the same, reference being had to the accompanying drawings, forming part of this specification, in which—

Figure 1 is a top view of my invention, when in position within a common stove-boiler.

Figure 2 is a cross-section of the same through the line $x x$ of fig. 1.

Similar letters of reference indicate like parts.

The nature of this invention relates to the cleansing of clothes by circulating boiling water through them.

The invention consists of devices set forth in the following:

A A A A are four pipes, arising from the bottom plate $b b$, which fits within the boiler C, as shown.

The said pipes A are formed with base-chambers, B, which are soldered to the plate $b b$, and open into the space $m m$, between the bottom, E, of the boiler, and the bottom plate $b b$, the latter plate being raised by the flange $o o$, which is soldered to the plate $b b$, and to the perforated plate $a a$, leaving an enclosed space, $n n$, between them, as shown.

v-shaped plates, $d d$, $d d$, $d d$, are affixed immediately underneath the slot-openings $e e$ made in the plate $b b$, whereby the water within the space $n n$ escapes downward into the space $m m$, and is again forced upward through the base-chambers B into the pipes A, and thence out through the curved spouts $f f f$, where it falls upon the clothes, and passes downward again through them, to be again circulated, as above described.

The caps D, to which the spouts $f f f$ are soldered, fit with easy contact upon the pipes A A A, as shown, and are slipped up or down upon the said pipes, to adjust the apparatus to boilers of different heights, and are to be removed to permit the placing of the clothes in the boiler.

G is a faucet, for drawing off the dirty water from the boiler.

Having thus described my invention,

I claim as new, and desire to secure by Letters Patent—

The removable caps D, with their branch-spouts f, when combined with the perforated and slotted plates $a b$, as herein shown and described.

DANIEL KELLOGG.
